DESIGN FOR A BOX

Justin I. Kingson, Mount Vernon, N. Y., assignor to Millburn Mills, Inc., New York, N. Y., a corporation of New York

Application May 15, 1943, Serial No. 110,212

Term of patent 7 years

To all whom it may concern:

Be it known that I, Justin I. Kingson, a citizen of the United States, residing at 6 Central Parkway, city of Mount Vernon, Westchester County,
State of New York, have invented a new, original, and ornamental Design for a Box, of which the following is a specification, reference being had to the accompanying drawing, forming part thereof.

Figure 1 is a front view of a box embodying my new design, and

Figures 2 and 3 are respectively top and end views of the same.

The back of the box is plain.

I claim:

The ornamental design for a box, substantially as shown and described.

JUSTIN I. KINGSON.
